WALER SUPPORT

Chester I. Williams, Grand Rapids, Mich.

Application June 22, 1950, Serial No. 169,732

3 Claims. (Cl. 25—131)

1

This invention relates to concrete forms and more particularly it relates to an improved device or waler support for supporting walers for concrete forms.

Prior to my invention, wooden cleats have been used to support walers. Usually a 1" x 4" or 1" x 6" plank is cut off about a foot long, and four or five nails are used to nail the cleat to the stud under the waler. The removal of this form of wooden cleat usually means a complete loss thereof, because by the time it is knocked off it usually splits, and not only is not suitable for re-use, but the parts left lying around with nails sticking up on the job create a job hazard.

Also some contractors nail their walers together which means that both the upper and lower walers break joints at the same place. Although the walers may be supported on the clamp, this is not a satisfactory system of erecting walers. Still others toe-nail the walers to the stud. This is also objectionable since it breaks up the lumber when the toe-nailing breaks loose, splitting out the lumber, etc.

It is therefore a principal object of the invention to provide an improved waler support overcoming the disadvantages of conventional wooden cleats.

Another object of the invention is to provide a waler construction in which the joints may be broken giving a more continuous support.

A further object of the invention is to provide a demountable waler support for waler construction in which the walers and waler supports may be readily erected in the construction of concrete forms and dismantled for further re-use without destruction.

Another object of the invention is to provide an improved waler construction which eliminates the necessity of building scaffolding to install clamps and the placing and replacing of wooden cleats.

Still another object of the invention is to provide an improved waler support which may be rotated out of the way when storing sections of concrete forms to which they are applied.

A further object of the invention is to permit, with the use of the improved waler support, breaking joints of upper and lower walers at different places.

The invention also has among its objects the production of an improved waler support which is simply fabricated, reliable, durable, economical, inexpensive, easily installed and satisfactory for its purpose.

In order to accomplish the various objects of 55 the invention, I have provided an improved waler support fabricated in the form of a trapezoid from relatively light gauge sheet metal which will support all the necessary loading or weight

5 that will be placed on a waler with the use of only two nails. It is so constructed that it may be rotated or swung back out of the way by pulling the lower nail and left in place on the studs of the form for re-use after the walers are removed. 10 The waler support is provided, for example, with two projecting members that abut against the stud for alignment and help take the load that is placed upon the waler itself. The metal waler support has holes on either side and the gauges 15 are located so that a substantially symmetrical waler support is formed so that it may be reversed and used on the opposite sides of the stud.

Many other objects and advantages of the construction herein shown and described will be obvious to those skilled in the art from the disclosure herein given.

To this end my invention consists in the novel construction, arrangement and combination of parts herein shown and described and more particularly pointed out in the appended claims.

Referring now to the accompanying drawing forming part of the specification:

Fig. 1 is a view in elevation taken through a concrete form, partly in section, illustrating the use of the waler support of my invention;

Fig. 2 is an enlarged end view of the waler support of the construction illustrated in Fig. 1;

Fig. 3 is an enlarged plan view of the construction illustrated in Fig. 2;

Fig. 4 is an enlarged elevational view of a modified form of waler support, illustrating the stop for larger walers; and

Fig. 5 is an enlarged view of a modified construction for a projection for the waler support.

Referring now more particularly to the drawing, waler supports 10 are shown affixed to studs 11 of a conventional concrete form construction 12 which is formed by a plurality of oppositely positioned form members, the boards of each form being connected by nails or the like, or in any suitable manner, with the exteriorly vertically extending studs 11, and the studs being braced by longitudinally extending waler members 13.

The forms may be of any desired length and height, and the oppositely positioned form members are adapted to be dismantled and used repeatedly for pouring concrete walls of the same or different thicknesses, and the forms may be used either for the construction of vertical or

2

battered walls. The form members are fastened

together by a plurality of conventional fastening devices or form tie rods 14 similar to that shown in the drawing, the devices being suitably spaced, vertically and longitudinally, to provide requisite form rigidity.

The waler support 10 of my invention is preferably fabricated of 14 gauge sheet metal or $\frac{1}{8}$ " aluminum in the shape of a trapezoid as shown in Figs. 1 and 4. The waler support 10 is formed with an upper edge 15 adapted to support the waler construction 13 in either position of the support on opposite sides of the form or of a stud to which it is affixed. Both the upper edge 15 and lower edge 16 are formed with struck out projections 17 adapted to abut a front edge of the stud to which they are affixed for alignment, and to help take the load that is placed on the waler construction 13. Lateral edges 18 are preferably formed, as shown, so that the waler supports may be sheared from strip metal the width of a waler support with a minimum loss by alternating or reversing the pattern. It is also within the scope of the invention that the edges may be simply sheared straight across to fabricate a maximum number of supports with a minimum length of strip material from which the supports are formed. The shape of the edges shown is preferred to reduce the sharp corners and minimize the accident hazards due to unnecessarily sharp corners. Nail holes 19 are symmetrically positioned along the edges 18 through which preferably two double headed nails 20 are driven for affixing and erecting the waler supports 10 to their respective studs 11.

Referring to Figure 4, there is illustrated a modified waler support 10' which is similarly constructed as the waler support described with reference to Figs. 1, 2, and 3, but is provided with a stop construction 21 which may be affixed by spot welding, riveting, or the like, as indicated at 22, to the waler support 10' for receiving, for example, 4" or 6" walers 13', depending upon the size of the concrete form construction to be braced. The stop construction 21 is preferably formed from the same gauge sheet metal as the waler support to the shape shown with an upstanding projection 23 to limit the outward movement of the waler 13' when erected in place upon the waler support.

In Fig. 5 there is illustrated another form 24 of a waler support similar to that described with reference to Figs. 1 to 3, but illustrating another example of a modified projection 17'. In this embodiment, the blank for the waler support is substantially triangular in shape. The portion 25 is slit at 26 after which it is formed to the solid lines as shown by first bending a portion 27 along the line 28 at right angles to the portion 29 and then forming the edges so that the triangular portions take their respective positions 27' and 29' completing the projection 17'. An upper lug or projection 17 for the modified waler support may be similarly formed as previously described or so formed from the metal of the support to provide a suitable projecting member to gauge the waler support upon a stud to which it is affixed. It is also to be understood that suitable gauge members may be provided by welding or otherwise affixing separate members to the support to provide the projections without departing from the scope of the invention.

In constructing a concrete form using any of the prefabricated waler supports described, the waler supports 10 are affixed to the studs where

the tie rods or fastening devices 14 are to be erected. Each waler support is nailed in place preferably with two double headed nails 20. The walers 13 are erected in place on the waler supports. Each securing device 14 is then erected in place, as shown. These securing devices are of conventional construction comprising threaded waler rods 30 projected through aligned holes in the forms 12 and affixed to an intermediate rod or she-rod 31. The waler rods 30 may be temporarily supported by double headed nails 32 driven through holes in the waler rods or through, for example, a cotter key 33, positioned in a hole in the waler rod to hold the form members in fixed, spaced-apart relation. The nails prevent such rotation of the members 30 as might occur when the end brackets 34 are positioned in clamping engagement with the waler members 13 by the threading of the wing nuts 35. The brackets 34 are preferably fastened in vertical position to the waler members by nailing through suitable apertures (not shown). It is to be understood that the nails or other securing devices are removed before attempting to rotate and release the members 30, as is well understood in the art. Stud marks 36 are formed on the waler rods 30 to indicate the proper depth of the rods within the form.

The forms constructed with the waler supports described may be raised and relocated, as is well understood in the art. When the forms are dismantled for re-use or stored, the waler supports may be rotated, for example, to the dotted position 37 within the outline of the stud, Fig. 1, by removing the lower nail 20; and if necessary, loosening the upper nail, after which the upper nail may be resecured to prevent rotation of the waler support from its storage position.

It is thus obvious that there has been disclosed a simple and inexpensive form of waler support which eliminates nailing walers together and toe-nailing to the studs. It also eliminates building scaffolding where men can work on walers. Furthermore, placing and replacing of wooden cleats is eliminated. Also, there is no necessity for cutting upper and lower walers to match at breaking points at one place. Occupational hazards of stepping on nails in removed cleats is also avoided. Expended material due to wrecking is materially eliminated.

The improved waler supports of this invention work equally well on vertical or battered walls. Furthermore, these supports permit breaking joints of upper and lower walers at different places. Any length of waler may be used without cutting. In storing form sections, the waler supports may be rotated out of the way in piling. Also, they are demountable and no wrecking is necessary permitting greater salvage of lumber.

Having thus described my invention, it is obvious that various immaterial modifications may be made in the same without departing from the spirit of my invention; hence, I do not wish to be understood as limiting myself to the exact form, construction, arrangement and combination of parts herein shown and described, or uses mentioned.

What I claim as new and desire to secure by Letters Patent is:

1. As an article of manufacture, a prefabricated metal reversible trapezoidal waler support for a concrete form construction adapted to be mounted on a stud thereof, lug means formed upon the

opposite parallel edges of the trapezoidal shaped waler support at substantially the center line thereof and adapted to abut an edge of the stud to which the waler support is affixed so that the waler support is substantially symmetrical in its reversed position, the upper edge of the waler support being adapted to support a waler member, and perforations symmetrically located adjacent the opposite inclined edges of the waler support, said perforations being constructed and arranged for receiving means for affixing the waler support to the stud in either of its erected positions on opposite faces of a stud.

2. The combination with a concrete form construction including sheathing and studding, and waler members adapted to be positioned transversely with respect to the studding, of a plurality of trapezoidal shaped plate-like waler supporting means symmetrically shaped and adapted to be affixed to the side surfaces of the studding, each of said waler supporting means including lug-shaped means symmetrically formed at substantially the center line thereof and from opposite edges of the waler supporting means and adapted to abut the front edge of the studding abutting the waler members to which the waler supporting means is affixed for positioning the waler supporting means on the studding, and perforations symmetrically located adjacent the

opposite edges of the waler supporting means, said perforations constructed and arranged for affixing the waler supporting means to the studding in either of their erected positions on opposite faces of one of said studding.

3. The combination with a concrete form construction including sheathing and studding, and waler members adapted to be positioned transversely with respect to the studding, of trapezoidal shaped waler supporting means adapted to be affixed to the side surfaces of the studding and engaging the edges of the studding abutting the waler members, lug means formed from the opposite parallel edges of said trapezoidal shaped waler supporting means adapted to transmit the loading of said waler members to the studding, said lug means being formed at substantially the center line of said trapezoidal shaped waler supporting means whereby the waler supporting means is reversible.
